UNITED STATES PATENT OFFICE.

WILLIAM WILSON, OF LONDON, ENGLAND.

ORRERY, TELLURION, AND THE LIKE.

1,256,855.

Specification of Letters Patent. Patented Feb. 19, 1918.

Application filed May 15, 1917. Serial No. 168,832.

To all whom it may concern:

Be it known that I, WILLIAM WILSON, a subject of the King of England, residing in London, England, have invented certain new and useful Improvements in Orreries, Tellurions, and the like, of which the following is a specification.

The purpose of the present invention is the construction of a tellurion which while 10 suitable for lecture purposes and correctly designed from a scientific point of view has the following special advantages:—

The motions of revolution and rotation of 15 the sun, earth and moon are obtained through the action of cords and pulleys instead of the complicated and costly combinations of spur-wheels, bevel-gearing and the like which have been used in some of the tellurions previously proposed.

Any possible irregularity in action 20 through the slackness or over-tension of the driving cords is prevented by the arrangement of a tension regulator for each cord.

The initial motion for actuation of the 25 device is obtained by the pressure of the hand on the tail piece of the horizontal bar hereinafter described and from this motion all the other movements are automatically obtained.

30 In the accompanying drawings—

Figure 1 is a side elevation of a tellurion constructed according to the present invention:

Fig. 2 is a view of a portion of Fig. 1, 35 partly in section in the plane of said Fig. 1;

Fig. 3 is a sectional elevation of a part of Fig. 1 by which the moon-model is caused to rise and fall;

Figs. 4, 5 and 6 are cross-sections on the 40 lines 4—4, 5—5 and 6—6 respectively of Fig. 3;

Figs. 7 and 8 are views at right-angles to one another of a rocking-lever hereinafter referred to;

45 Fig. 9 is a section to a scale larger than that of Fig. 1, of the lower portion of the supporting base hereinafter referred to, and of the parts immediately above it;

Fig. 10 is a plan of a driving-wheel 50 constituted by a series of swan-necks A³⁰, hereinafter referred to, situated below the said supporting base and hereinafter particularly described;

Fig. 11 is a section of a sun-supporting 55 and driving device forming part of the apparatus that is shown in Fig. 1; and

Fig. 12 is a perspective view of an expandible wheel of the kind that is employed in Fig. 1.

Like reference letters indicate like parts 60 throughout the drawings.

With reference to the drawings:—

A vertical shaft C¹ supporting at its upper end a sun globe S is rigidly fixed at its lower end into a substantial base, constituted 65 by the parts B² and B¹.

Rigidly fixed to this shaft are four driving-wheels lettered D, E, G and H respectively by means of which the required motions are transmitted to the various parts of the apparatus. These four driving-wheels, from 70 below upward are as follows:—

The wheel D is the "Pole-Star wheel" concerned with the maintenance of the constant direction of the earth's inclined axis. 75

The wheel E is the "Saros wheel" concerned with the slow revolution of the moon's nodes constituting the Saros cycle.

The wheel G is the "moon-revolution wheel", whereby the moon in the tellurion is 80 made to travel around the earth.

The wheel H is the "sun-rotation wheel", for rotating the sun on the solar axis.

A main horizontal tubular bar is made up 85 of the parts F¹ F² F³, pivoted on the shaft C¹. This moves freely in a horizontal plane around the vertical shaft C¹ as a center and projecting in both directions terminates at one end in a balance weight BW which serves also as a handle and at the other end 90 in a T piece J supporting the mechanism concerned with the position and motions of the earth M¹¹ and moon O¹⁴.

The earth's vertical support consists of a triple concentric tubular spindle supported 95 in a vertical position in the tubular bracket or T-piece J, and in its turn supporting the earth and moon ecliptic and orbital rings and mechanisms connected therewith. Its construction and its relationships are as 100 follows: The innermost tube M of this triple tubular spindle is freely rotatable within an intermediate tube L and an outermost tube K⁵ and is supported in position by a fixed collar or shoulder M¹ on it by which it rests 105 on the top of the tube L and projects above that encircling tube and thus affords means of attachment for the angle bracket M⁴ supporting the earth M¹¹ on its inclined axis. It projects below its encircling tube and thus 110 affords means of attachment for a pulley "Pole Star pulley" M², connected by an end-

less driving-cord I with the driving wheel "Pole Star wheel" D on the vertical shaft C¹, which drives the "Pole Star pulley" when the latter is moved by the bar F¹ F² F³ in relation to the shaft C¹. The ratio between this driving wheel D and pulley M² is such that when the bar F¹ F² F³ is made to revolve about the shaft C¹ the earth's axis maintains a constant direction in space, *e.g.* to an imaginary pole star. Similarly the intermediate movable tube L of the aforesaid triple tubular spindle is freely rotatable within its encircling tube K⁵ upon operation of the bar F¹ F² F³ and is supported in position by a collar or shoulder L¹ which is fixed on the tube L and by which it rests on the top of the sleeve K, which latter forms a virtual upward extension of the T-piece J and is stationary on the latter. The tube L projects above its encircling tube K⁵ and thus affords means of attachment for two structures concerned in the slow revolution of the moon's nodes.

One of the structures is an inclined disk or cam L³ supporting a rocking lever P¹ P² causing the moon O¹⁴ in its "monthly" revolution successively to rise above and fall below the ecliptic.

The other structure is a horizontal bar L⁵ and vertical rods L⁶ supporting a ring L⁸ surrounding the earth but at some distance from it, and in a plane oblique to the ecliptic, and supporting also a ring L⁷ somewhat smaller and in the plane of the ecliptic; thus the one ring L⁸ represents the plane of the moon's orbit, and together the rings L⁷ L⁸ indicate the situation of the moon's nodes.

The aforesaid tube L projects below its encircling sleeve K⁵ and thus affords means of attachment for a pulley, the "Saros pulley" L², connected by an endless cord 2 with the driving wheel "Saros wheel" E on the vertical shaft C¹. The ratio between this driving wheel E and corresponding pulley L² is such that when the bar F¹ F² F³ is made to revolve a slow revolution of the moon's nodes is seen to occur corresponding to a complete revolution in 18 years 11 days or the period known as the cycle of Saros.

In addition to the two above-mentioned structures L³ L⁶ which are rigidly attached by set screws to the upward prolongation of the rotatable tubular spindle L and thus move with it, there is situated between the said structures a third structure, the rocking lever P¹ P² resting by wheels W on the surface of the inclined cam-disk L³. This rocking-lever unlike its adjacent structures is not fixed to the tubular spindle L by which it is centered but is capable of any rotatory motion around that spindle which may be imparted to it. Such rotatory motion is imparted to it by the vertical moon spindle O¹ which is embraced by the forked termination P⁹ of the rocking-lever, and thus the

monthly revolution of the moon necessitates a concurrent monthly revolution of the rocking-lever. Again, the rocking-lever in virtue of a universal-joint connection UJ (Figs. 7 and 8) with the spindle L is also capable of a rocking or see-saw motion in the vertical plane. Such a motion is imparted to it during its monthly revolution in virtue of the rise and fall of its supporting-wheels W necessitated by the inclined situation of the cam-disk L³ on which they roll. The inclination of the inclined disk corresponds to the inclination of the moon's orbit and that diameter of the inclined disk which is horizontal corresponds to the nodal line of the moon's orbit and may be called the disk's nodal line. When the rocking-lever wheels W rest on this line the rocking-lever is horizontal and the moon is in the plane of the ecliptic, in other words at its nodes; when the wheels W rest on any other points of the disk above or below its nodal line the moon occupies the corresponding position above or below the ecliptic, as will hereinafter appear. As the inclined disk L³ is fixed to its supporting spindle L it slowly rotates with it, completing one revolution in a period corresponding to 18 years 11 days, and as it rotates its nodal line necessarily rotates and consequently the nodal line of the moon's orbit also; in other words, the slow revolution of the moon's nodes takes place.

The third and outermost tube K⁵ of this aforesaid triple tubular spindle turns about the fixed sleeve K and is upborne by the top end of the T-piece J. It carries a pulley ("moon's revolution pulley") K⁵⁰ fixed to it and connected by a cord 3 with a large driving wheel "moon's revolution wheel" G firmly clamped to the vertical shaft C¹. This moon revolution pulley K⁵⁰ by means of its upper flange is rigidly connected to a horizontal bar N carrying fixed to it at one end the rigid vertical spindle O¹ supporting the moon O¹⁴ non-rotatably on that spindle, and supporting also the moon's hemispherical shadow cap O¹¹ and the special mechanism relating to the motion of the shadow cap to be referred to subsequently herein. The ratio between the last-named driving wheel G and corresponding pulley K⁵⁰ is such that when the horizontal bar of the apparatus is made to revolve there occur 13.39 complete revolutions of the moon around the earth, or 12.39 lunations occur during the yearly revolution of the earth around the sun, and also that 223 lunations occur during the Saros cycle of 18 years 11 days and 235 lunations occur during the metonic cycle of 19 years.

By the mechanisms above referred to the following motions and positions are concurrently obtained.

1. Constant direction of the earth's axis. 130

2. Monthly revolution of the moon around the earth, in a plane oblique to the ecliptic.
3. The slow revolution of the moon's nodes.
- 5 In addition to the mechanism just referred to for obtaining the moon's revolution in a plane oblique to the ecliptic, special means are employed so as to demonstrate the following additional motions of the 10 moon:—
1. The monthly rotation of the moon on its axis.
  2. The revolution of the "shadowed half" of the moon so as to maintain a constant 15 direction away from the sun.
  3. The successive phases of the moon.
  4. The production of solar eclipses total, partial and annular.
- The moon's monthly rotation on its axis 20 is effected because it is non-rotatable in relation to the spindle O^1 and bar N ; this may be brought about by the following means:— The moon's steel spindle O^1 as regards its upper half has one side flattened so that its 25 section is angular, *e. g.*, semi-circular instead of circular. The central circular bore (lined by a tube) passing through the moon and by which it is guided as it slides up and down on the spindle is similarly altered in 30 cross-section at one part of its length, say by the insertion of a piece of metal so that while freely movable in the vertical direction all rotatory motion relatively to its rigid spindle O^1 is prevented. The spindle 35 being rigidly fixed as hereinbefore stated it necessarily has the same side always toward the earth and consequently the same condition obtains in the case of the moon itself, and this condition implies one rotation 40 on its axis in the course of its one revolution around the earth.
- The revolution of the darkened side of the moon so as to maintain it in a constant direction away from the sun will next be described. In some tellurions wherein a rocking-lever is employed, the rocking-lever ends in an upward-curving bar reaching to the level of the ecliptic, and to its extremity is rigidly attached the moon globe. This arrangement 45 permits of the moon's revolution in the plane oblique to the ecliptic and also permits of the moon presenting the same side constantly to the earth but such an arrangement is incapable of representing the revolution of the moon's dark side in its 50 constant direction away from the sun and consequently the phases of the moon cannot be represented automatically nor would it be possible by the addition to this known 55 device of any conical attachment such as is hereinafter described, to represent the various forms of solar eclipses. In the tellurion of the present invention herein described all 60 these can be represented by the employment 65 of the following means:—The dark side of

the moon is represented by a hemispherical cap O^{11} painted black applied to the surface of the moon but free to move around it without actually touching it. It is supported in such a way that while free to move 70 up and down with the moon it is capable of an independent rotatory motion around the moon and the motion thus conveyed to it is such that it constantly maintains direction away from the sun. This is effected by the 75 following means:—The rigid moon spindle O^1 is surrounded as to its lower half by a freely rotatable tube O^5 having at its lower end a flange O^6 resting on a pulley O^4 rotatable around the base of the spindle O^1 . The 80 flange O^6 and pulley O^4 are engaged with one another. The pulley is connected by a driving cord 4 with a similar-sized pulley K^6 rigidly fixed to the upper end of the sleeve K previously described. Outside the 85 tube O^5 loosely encircling the moon's rigid spindle is a short tube O^7 free to move up and down and fitted with two flanges O^{71} and O^{72} between which it is embraced by the fork P^o of the rocking-lever. 90 By means of a fine round bar O^8 this movable short tube O^7 is rigidly connected with a second short tube O^9 on which the moon rests and to which the hemispherical moon-cap O^{11} is attached by a loose collar engaging a tail-piece O^{13} on the cap and held by a set-screw O^{12} . Thus the upward and downward motion conveyed by the rocking-lever P^1 P^2 to the short-tube O^7 is thence transmitted to the hemispherical moon-cap 100 O^{11} and to the moon O^{14} while at the same time the requisite rotatory motion in relation to the spindle O^1 is conveyed to the hemispherical cap alone, by means of the bar O^8 actuated by the pulley O^4 and tube 105 O^5 immediately surrounding the rigid moon-spindle. The rotatory motion of the above-mentioned pulley O^4 and tube O^5 is transmitted to the moon-cap through the medium of a flange O^{10} on the upper end of the tube 110 O^5 in which is filed a slot receiving the rod O^8 which as before described connects together the lower and upper portions of the moon-support O^7 and O^9 . By this combination of mechanism the hemispherical 115 moon-cap (representing the dark side of the moon) has transmitted to it an up and down motion due to its connection with the rocking-lever and also a rotatory motion around the moon due to its connection with the revolving tube O^5 surrounding the moon's rigid spindle O^1 .

The above-described mechanism, causing the dark side of the moon to maintain a constant direction away from the sun supplies 125 all the conditions necessary for demonstrating the various phases of the moon as observed from the earth.

As to eclipses:—An aluminium truncated cone representing the conical shadow of the 130

moon cast into space can be attached to the convex surface of the hemispherical moon-cap O^{11} or substituted therefor as indicated by the chain-lines AT, Fig. 3, and thus partaking of the motion of the cap it is always directed away from the sun and at certain times in the year the tail-end of this shadow-piece is seen to travel across the face of the earth, and affords a correct demonstration of 10 solar eclipses total, and partial. A similar cone shown by chain-lines X in Fig. 3 but shorter and pointed instead of being truncated can be used on the moon to represent the shadow cast by the moon when the respective distances between the sun, earth and moon are such as to give rise to an annular or ring-like eclipse.

As to the earth's-rotation mechanism:— Under the central base of the apparatus is a 20 thin steel foundation-plate A^1 supporting the whole apparatus through the intervention of leveling-screws such as B^2 . Connected with the steel foundation-plate are 12 radiating bars A^3 turned up at their outer 25 ends as at A^{30} . These 12 vertical terminals or swan-necks A^{30} practically constitute a large wheel, see Fig. 10. An endless band of cord 5 is employed the greater part of which encircles the 12 swan-neck terminals 30 A^{30} , the remaining portion passes thence into the lower end of, and up, the central tube M supporting the earth M^{11} and emerges at the top as a loop of cord. In this upper loop is the upper member M^8 of the earth's-rotation duplex auxiliary pulley $M^7 M^9$ mounted on the angle-bracket M^4 . Thus this driving-band 5 encircles at one end the ring of swan-neck terminals and at its other end the earth's-rotation auxiliary pulley $M^7 M^9$, 35 while the intermediate portion is contained 40 in the central vertical tube M. It thus constitutes a driving belt connecting together a large driving wheel composed of the circle of swan-neck terminals A^{30} and the lower 45 member M^7 of the small driven auxiliary pulley $M^7 M^8 M^9$ which in turn communicates its motion to the earth's-rotation pulley by the upper member M^9 of the auxiliary pulley $M^7 M^8 M^9$ which is geared by a short 50 endless band 6 to a pinion M^{10} integral with a long sleeve connected with the earth M^{11} , the pinion, the sleeve and the earth being all 55 rotatable about the inclined shaft M^{12} by which the earth is carried, and which is secured to the arm M^4 . If the apparatus remains stationary and the cord 5 be made to slide around the circle of swan-necks A^{30} rotatory motion would be conveyed to the earth. Similarly if the cord 5 were held stationary 60 and the apparatus made to revolve the same rotatory motion would be conveyed to the earth. The cord can be permanently secured to one of the swan-necks or temporarily fixed by the pressure of the 65 finger and thus the initial movement by the

hand on the tail-piece of the bar $F^1 F^2 F^3$ causing the earth to revolve around the sun automatically causes the earth to rotate on its own axis.

As to the sun's-rotation mechanism:— 70 Firmly attached to the central vertical shaft C^1 by a powerful set-screw H^2 and immediately above the moon-revolution driving-wheel G is situated the sun-rotation driving wheel H which by means of endless driving 75 bands 7 and 8 conveys the requisite rotatory motion to the sun-rotation pulley H^6 running loosely on the central vertical shaft C^1 and situated immediately above the sun-rotation driving wheel H. Motion of the sun-rotation driving pulley H^6 is obtained from the sun-rotation driving-wheel H through the intervention of a pair of united auxiliary pulleys H^3 and H^4 attached to a common tubular support running on a vertical spindle 80 H^{10} rising from the tail piece F^2 of the horizontal bar $F^1 F^2 F^3$, and the ratio between the driving-wheel H and pulley H^6 together with the ratio between the two united pulleys $H^3 H^4$ is such that the sun makes one 90 rotation on its own axis in 26 days, or about 14 rotations in the year.

The rotatory motion of the sun's-rotation pulley H^6 is conveyed to the sun S on its inclined axis I^1 (see Fig. 11) by the intervention of a tubular sun-driving sleeve I^4 rotatable freely on the vertical shaft C^1 . The sleeve I^4 interlocks with the flange of the sun-rotation pulley by means of a pin p (see Fig. 9) and hole. A shaft I^2 100 bent at its upper portion I^1 to the required angle to constitute the sun's inclined axis is inserted into the shaft C^1 and is secured thereto by a key and slot connection such that the sun's inclined axis points in the 105 right direction.

The rotatory motion of the sun S is effected by a vertical pin I^5 in the flange of the tube I^4 fitting loosely near the sun's south pole into a slot in the flange of an axial tube I^6 in the sun. As the sun's inclined axis at the south pole is in the central line of the sun's support it follows that the actual center of the sun is a slight distance from the central line and thus without any attempt to make the earth revolve in an elliptical orbit an important point is gained namely, that the sun does actually occupy a position eccentric to the earth's orbit, the earth being thus nearer to the sun at one time of the year than at another and thus demonstrating the periods of the year when the earth is at its perihelion and aphelion respectively.

Where important motions or combinations of motions render great accuracy essential this is attainable by the employment of driving-wheels G and E capable of expansion. The method adopted in the construction of these expansion wheels, is as 125 130

follows, and is described with reference to the wheel G of Fig. 1 illustrated separately in perspective in Fig. 12, it being understood that the wheel E is substantially similar and that neither wheel is of itself of the present invention:—The wheel is divided through the center into two semi-circular portions g^1 g^2 hinged together at one end of the dividing line by the pin g^3 and opening out at the other end. This gap can be increased or diminished by the action of an adjustment screw g^4 . The wheel is mounted between two plates g^5 g^6 one half g^1 of the wheel being permanently secured 10 to these plates while the other half g^2 is freely movable between them and after adjustment can be tightened or loosened by the turn of winged nuts and bolts g^7 passing through corresponding holes in the plates 15 and through slots in the adjustable half of the wheel which permit of the requisite mobility while the halves are being adjusted and perfect immobility after adjustment has been effected. Great accuracy in 20 results is thus obtainable, illustrated by the following figures. The Saros driving wheel E can be so adjusted that an error of not more than one day occurs in the whole Saros cycle of 18 years 11 days or an error 25 of one in 6,584. The moon-revolution driving-wheel G can be so adjusted that the number of lunations in the Saros cycle is $223\frac{1}{12}$ th, instead of 223, and it is only a matter of still more careful adjustment to 30 obtain still more accurate results.

To regulate the tension of the various endless bands 1, 2, 3, 4 and 8 jockey pulleys Q^3 Q^4 Q^5 H^7 N^2 carried on the parts F^1 H^8 and N respectively are applied to them in 40 a manner well understood and not of itself of this invention.

What I claim as my invention and desire to secure by Letters Patent is:—

1. In a tellurion, the combination of a 45 base, a vertical shaft fixed in and extending upwardly from the base, a plurality of stationary wheels secured on the aforesaid vertical shaft and co-axial therewith, a horizontal bar pivoted to the aforesaid vertical shaft and movable about it in the horizontal plane, three concentric spindles, innermost, intermediate and outermost, together constituting a triple spindle and borne on one arm of the horizontal bar perpendicularly thereto and each rotatable independently of its companion about their common axis, three pulleys one secured to each of said three spindles, three endless bands constituting each an operative connection between a pulley on one of the said concentric spindles and a corresponding stationary wheel in the aforesaid plurality, an earth-model borne on the top of the innermost spindle, a cam fixed aslant upon the intermediate spindle, a moon-model bored axially, a spindle which at its upper end engages the moon-model and prevents relative rotation between it and the said spindle and at its lower end is operatively connected to the 50 outermost of the three concentric spindles aforesaid to turn therewith but not relatively thereto, an operative connection between the aforesaid cam and the moon-model to raise and lower that model by moving it along the spindle of angular cross-section, a rocking lever which is pivoted to a sleeve loosely encircling the aforesaid intermediate spindle, is engaged with the aforesaid cam and is in operative connection with the moon-model spindle of angular cross-section to be moved by that spindle around the axis of the innermost spindle, a shadow-cap engaging one side of the moon-model, a rotatable driving-sleeve encircling the lower portion of the spindle by which as aforesaid the angular bore of the moon-model is engaged, two pulleys one fixed to the said driving-sleeve the other fixed to the horizontal bar aforesaid, and 55 60 65 70 75 80 85 90 95 100 105 110 115 120 125 130

ally, a spindle which at its upper end engages the moon-model and prevents relative rotation between it and the said spindle and at its lower end is operatively connected to the outermost of the three concentric spindles aforesaid to turn therewith but not relatively thereto, an operative connection between the aforesaid cam and the moon-model to raise and lower that model by moving it along the spindle of angular cross-section, a rocking lever which is pivoted to a sleeve loosely encircling the aforesaid intermediate spindle, is engaged with the aforesaid cam and is in operative connection with the moon-model to raise and lower that model by moving it along the spindle of angular cross-section and to be moved by the same spindle around the axis of the intermediate spindle.

2. In a tellurion, the combination of a base, a vertical shaft fixed in and extending upwardly from the base, a plurality of stationary wheels secured on the aforesaid vertical shaft and co-axial therewith, a horizontal bar pivoted to the aforesaid vertical shaft and movable about it in the horizontal plane, three concentric spindles, innermost intermediate and outermost, together constituting a triple spindle and borne on one arm of the horizontal bar perpendicularly thereto and each rotatable independently of its companion about their common axis, three pulleys one secured to each of said three spindles, three endless bands constituting each an operative connection between a pulley on one of the said concentric spindles and a corresponding stationary wheel in the aforesaid plurality, an earth-model borne on the top of the innermost spindle, a cam fixed aslant upon the intermediate spindle, a moon-model bored axially, a spindle which at its upper end engages the moon-model and prevents relative rotation between it and the said spindle and at its lower end is operatively connected to the outermost of the three concentric spindles aforesaid to turn therewith but not relatively thereto, an operative connection between the aforesaid cam and the moon-model to raise and lower that model by moving it along the spindle of angular cross-section, a rocking lever which is pivoted to a sleeve loosely encircling the aforesaid intermediate spindle, is engaged with the aforesaid cam and is in operative connection with the moon-model spindle of angular cross-section to be moved by that spindle around the axis of the innermost spindle, a shadow-cap engaging one side of the moon-model, a rotatable driving-sleeve encircling the lower portion of the spindle by which as aforesaid the angular bore of the moon-model is engaged, two pulleys one fixed to the said driving-sleeve the other fixed to the horizontal bar aforesaid, and

an endless band encircling these two pulleys, and a rising and falling splined connection actuated by the rocking lever and also by the driving-sleeve and connecting said driving-sleeve and shadow-cap to turn the latter about the spindle of angular cross-section and to raise and lower the shadow-cap and moon-model.

3. In a tellurion, the combination of a base, a vertical shaft fixed in and extending upwardly from the base, a plurality of stationary wheels secured on the aforesaid vertical shaft and co-axial therewith, a horizontal bar pivoted to the aforesaid vertical shaft and movable about it in the horizontal plane, three concentric tubular spindles, innermost intermediate and outermost, together constituting a triple spindle and borne on one arm of the horizontal bar perpendicular thereto and each rotatable independently of its companion about their common axis, three pulleys one secured to each of said three spindles, three endless bands constituting each an operative connection between a pulley on one of the said concentric spindles and a corresponding stationary wheel in the aforesaid plurality, an earth-model borne on the top of the innermost spindle, a cam fixed aslant upon the intermediate spindle, a moon-model bored axially, a spindle which at its upper end engages the moon-model and prevents relative rotation between it and the said spindle and at its lower end is operatively connected to the outermost of the three concentric tubular spindles aforesaid to turn therewith but not relatively thereto, an operative connection between the aforesaid cam and the moon-model to raise and lower that model by moving it along the spindle of angular cross-section, a rocking lever which is pivoted to a sleeve loosely encircling the aforesaid intermediate spindle, is engaged with the aforesaid cam and is in operative connection with the moon-model to raise and lower that model by moving it along the spindle of angular cross-section and to be moved by the same spindle around the axis of the intermediate spindle, an earth-model, an inclined spindle about which that model is rotatable and which is fixed to the innermost tubular spindle aforesaid and lies aslant in relation thereto, a driving wheel below the aforesaid base and driving pinion secured to the earth-model, an auxiliary duplex pulley carried on a support borne by the innermost tubular spindle, an endless band encircling the driving pinion and one member of the auxiliary duplex pulley, and an endless band both sides of which pass through the bore of the innermost tubular spindle and one end of which embraces the other member of the auxiliary duplex pulley while the other end encircles the said driving wheel.

4. In a tellurion, the combination of a base, a vertical shaft fixed in and extending upwardly from the base, a plurality of stationary wheels secured on the aforesaid vertical shaft and co-axial therewith, a horizontal bar pivoted to the aforesaid vertical shaft and movable about it in the horizontal plane, three concentric tubular spindles, innermost intermediate and outermost, together constituting a triple spindle and borne on one arm of the horizontal bar perpendicular thereto and each rotatable independently of its companion about their common axis, three pulleys one secured to each of said three spindles, three endless bands constituting each an operative connection between a pulley on one of the said concentric spindles and a corresponding stationary wheel in the aforesaid plurality, an earth-model borne on the top of the innermost spindle, a cam fixed aslant upon the intermediate spindle, a moon-model bored axially, a spindle which at its upper end engages the moon-model and prevents relative rotation between it and the said spindle and at its lower end is operatively connected to the outermost of the three concentric tubular spindles aforesaid to turn therewith but not relatively thereto, an operative connection between the aforesaid cam and the moon-model to raise and lower that model by moving it along the spindle of angular cross-section, a rocking lever which is pivoted to a sleeve loosely encircling the aforesaid intermediate spindle, is engaged with the aforesaid cam and is in operative connection with the moon-model to raise and lower that model by moving it along the spindle of angular cross-section and to be moved by the same spindle around the axis of the intermediate spindle, an earth-model, an inclined spindle about which that model is rotatable and which is fixed to the innermost tubular spindle aforesaid and lies aslant in relation thereto, a driving wheel constituted by a series of radial arms having swan-necked ends and situated below the aforesaid base, a driving pinion secured to the earth-model, an auxiliary duplex pulley carried on a support borne by the innermost tubular spindle, an endless band encircling the driving pinion and one member of the auxiliary duplex pulley, and an endless band both sides of which pass through the bore of the innermost tubular spindle and one end of which embraces the other member of the auxiliary duplex pulley while the other end encircles the said driving wheel.

5. In a tellurion, the combination of a base, a vertical shaft fixed in and extending upwardly from the base, a plurality of stationary wheels secured on the aforesaid vertical shaft and co-axial therewith, a horizontal bar pivoted to the aforesaid vertical shaft and movable about it in the horizontal plane, three concentric tubular spindles, innermost intermediate and outermost, together constituting a triple spindle and borne on one arm of the horizontal bar perpendicular thereto and each rotatable independently of its companion about their common axis, three pulleys one secured to each of said three spindles, three endless bands constituting each an operative connection between a pulley on one of the said concentric spindles and a corresponding stationary wheel in the aforesaid plurality, an earth-model borne on the top of the innermost spindle, a cam fixed aslant upon the intermediate spindle, a moon-model bored axially, a spindle which at its upper end engages the moon-model and prevents relative rotation between it and the said spindle and at its lower end is operatively connected to the outermost of the three concentric tubular spindles aforesaid to turn therewith but not relatively thereto, an operative connection between the aforesaid cam and the moon-model to raise and lower that model by moving it along the spindle of angular cross-section, a rocking lever which is pivoted to a sleeve loosely encircling the aforesaid intermediate spindle, is engaged with the aforesaid cam and is in operative connection with the moon-model to raise and lower that model by moving it along the spindle of angular cross-section and to be moved by the same spindle around the axis of the intermediate spindle, an earth-model, an inclined spindle about which that model is rotatable and which is fixed to the innermost tubular spindle aforesaid and lies aslant in relation thereto, a driving wheel constituted by a series of radial arms having swan-necked ends and situated below the aforesaid base, a driving pinion secured to the earth-model, an auxiliary duplex pulley carried on a support borne by the innermost tubular spindle, an endless band encircling the driving pinion and one member of the auxiliary duplex pulley, and an endless band both sides of which pass through the bore of the innermost tubular spindle and one end of which embraces the other member of the auxiliary duplex pulley while the other end encircles the said driving wheel.

plane, three concentric spindles, innermost intermediate and outermost, together constituting a triple spindle and borne on one arm of the horizontal bar perpendicularly thereto and each rotatable independently of its companion, about their common axis three pulleys one secured to each of said three spindles, three endless bands constituting each an operative connection between 5 a pulley on one of the said concentric spindles and a corresponding stationary wheel in the aforesaid plurality, an earth-model borne on the top of the innermost spindle, a cam fixed aslant upon the intermediate 10 spindle, a moon-model bored axially, a spindle which at its upper end engages the moon-model and prevents relative rotation between it and the said spindle and at its lower end is operatively connected to the 15 outermost of the three concentric spindles aforesaid to turn therewith but not relatively thereto, an operative connection between the aforesaid cam and the moon-model to raise and lower that model by moving 20 it along the spindle of angular cross-section, a rocking lever which is pivoted to a sleeve loosely encircling the aforesaid intermediate spindle, is engaged with the aforesaid cam and is in operative connection 25 with the moon-model to raise and lower that model by moving it along the spindle of angular cross-section, a rocking lever which is pivoted to a sleeve loosely encircling the aforesaid intermediate spindle, is engaged with the aforesaid cam and is in operative connection 30 with the moon-model to raise and lower that model by moving it along the spindle of angular cross-section and to be moved by the same spindle around the axis of the intermediate spindle, a sun-model, a rotatable 35 sun-driving sleeve and pinion engaged with one another and encircling the aforesaid vertical shaft, a stationary sun-driving wheel secured on the said vertical shaft, a vertical spindle fixed to and rising from the aforesaid 40 horizontal bar, a pair of connected auxiliary pulleys on that vertical spindle and flexible means operatively connecting the sun-driving pinion with the stationary sun-driving wheel by way of the said connected 45 auxiliary pulleys.

6. In a tellurion, the combination of a base, a vertical shaft fixed in and extending upwardly from the base, a plurality of stationary wheels secured on the aforesaid 50 vertical shaft and co-axial therewith, a horizontal bar pivoted to the aforesaid vertical shaft and movable about it in the horizontal plane, three concentric tubular spindles, innermost intermediate and outermost, together constituting a triple spindle and borne on one arm of the horizontal bar perpendicularly thereto and each rotatable independently of its companion about their common axis, three pulleys one secured to 55 each of said three spindles, three endless bands constituting each an operative connection between a pulley on one of the said concentric spindles and a corresponding stationary wheel in the aforesaid plurality, an 60 earth-model borne on the top of the inner- 65

most spindle, a cam fixed aslant upon the intermediate spindle, a moon-model bored axially, a spindle which at its upper end engages the moon-model and prevents relative rotation between it and the said spindle and at its lower end is operatively connected to the outermost of the three concentric tubular spindles aforesaid to turn therewith but not relatively thereto, an operative connection between the aforesaid cam and the moon-model to raise and lower that model by moving it along the spindle of angular cross-section, a rocking lever which is pivoted to a sleeve loosely encircling the aforesaid intermediate spindle, is engaged with the moon-model to raise and lower that model by moving it along the spindle of angular cross-section, a rocking lever which is pivoted to a sleeve loosely encircling the lower portion of the spindle by which as aforesaid the angular bore of the moon-model is engaged, two pulleys one fixed to the said driving-sleeve the other 80 fixed to the horizontal bar aforesaid, and an endless band encircling these two pulleys, a rising and falling splined connection actuated by the rocking lever and also by the driving-sleeve and connecting said driving-sleeve and shadow-cap to turn the latter about the spindle of angular cross-section and to raise and lower the shadow-cap and moon-model, an earth-model, an inclined spindle about which that model is rotatable 85 and which is fixed to the innermost tubular spindle aforesaid and lies aslant in relation thereto, a driving wheel below the aforesaid base, a driving pinion secured to the earth-model, an auxiliary duplex pulley carried 90 on a support borne by the innermost tubular spindle, an endless band encircling the driving pinion and one member of the auxiliary duplex pulley, an endless band both sides of which pass through the bore of the 95 innermost tubular spindle and one end of which embraces the other member of the auxiliary duplex pulley while the other end encircles the said driving wheel, a sun-model, a rotatable sun-driving sleeve and pinion engaged with one another and encircling the aforesaid vertical shaft, a stationary sun-driving wheel secured on the said vertical shaft, a vertical spindle fixed to and rising from the aforesaid horizontal bar, a pair of 100 connected auxiliary pulleys on that vertical spindle, and flexible driving means operatively connecting the sun-driving pinion with the stationary sun-driving wheel by way of the said connected auxiliary pulleys. 105 7. In a tellurion, the combination of a base, a vertical shaft fixed in and extending upwardly from the base, a plurality of stationary wheels secured on the aforesaid vertical shaft and co-axial therewith, a horizontal bar pivoted to the aforesaid vertical shaft and movable about it in the horizontal plane, three concentric tubular spindles, innermost intermediate and outermost, together constituting a triple spindle and borne on one arm of the horizontal bar perpendicularly thereto and each rotatable independently of its companion about their common axis, three pulleys one secured to each of said three spindles, three endless bands constituting each an operative connection between a pulley on one of the said concentric spindles and a corresponding stationary wheel in the aforesaid plurality, an earth-model borne on the top of the inner- 110

zontal bar pivoted to the aforesaid vertical shaft and movable about it in the horizontal plane, three concentric spindles, innermost intermediate and outermost, together constituting a triple spindle and borne on one arm of the horizontal bar perpendicularly thereto and each rotatable independently of its companion about their common axis, three pulleys one secured to each of said 5 10 15 20 25 30 35 40 45 50 55 60 65 70 75 80 85 90 95 100 105 110 115 120 125 130

three spindles, three endless bands constituting each an operative connection between a pulley on one of the said concentric spindles and a corresponding stationary wheel in the aforesaid plurality, an earth-model borne on the top of the innermost spindle, a cam fixed aslant upon the intermediate spindle, a moon-model bored axially, a spindle which at its upper end engages the moon-model and prevents relative rotation between it and the said spindle and at its lower end is operatively connected to the outermost of the three concentric spindles aforesaid to turn therewith but not relatively thereto, an operative connection between the aforesaid cam and the moon-model to raise and lower that model by moving it along the spindle of angular cross-section, a rocking lever which is pivoted to a sleeve loosely encircling the aforesaid intermediate spindle, is engaged with the aforesaid cam and is in operative connection with the moon-model spindle of angular cross-section to be moved by that spindle around the axis of the innermost spindle, a shadow-cap engaging one side of the moon-model, a rotatable driving-sleeve encircling the lower portion of the spindle by which as aforesaid the angular bore of the moon-model is engaged, two pulleys one fixed to the said driving-sleeve the other fixed to the horizontal bar aforesaid, and an endless band encircling these two pulleys, a rising and falling splined connection actuated by the rocking lever and also by the driving-sleeve and connecting said driving-sleeve and shadow-cap to turn the latter about the spindle of angular cross-section and to raise and lower the shadow-cap and moon-model band-tightening devices for the endless bands aforesaid and screw expanding-devices for the circumferences of driving wheels engaged by said bands.

8. In a tellurion, the combination of a base, a vertical shaft fixed in and extending upwardly from the base, a plurality of stationary wheels secured on the aforesaid vertical shaft and co-axial therewith, a horizontal bar pivoted to the aforesaid vertical shaft and movable about it in the horizontal plane, three concentric tubular spindles, innermost intermediate and outermost, together constituting a triple spindle and borne on one arm of the horizontal bar perpendicularly thereto and each rotatable independently of its companion about their common axis, three pulleys one secured to each of said three spindles, three endless bands constituting each an operative connection between a pulley on one of the said concentric spindles and a corresponding stationary wheel in the aforesaid plurality, an earth-model borne on the top of the innermost 130

spindle, a cam fixed aslant upon the intermediate spindle, a moon-model bored axially, a spindle which at its upper end engages the moon-model and prevents relative rotation between it and the said spindle and at its lower end is operatively connected to the outermost of the three concentric tubular spindles aforesaid to turn therewith but not relatively thereto, an operative connection between the aforesaid cam and the moon-model to raise and lower that model by moving it along the spindle of angular cross-section, a rocking lever which is pivoted to a sleeve loosely encir-

the outermost of the three concentric spindles aforesaid to turn therewith but not relatively thereto, an operative connection between the aforesaid cam and the moon-model to raise and lower that model by moving it along the spindle of angular cross-section, a rocking lever which is pivoted to a sleeve loosely encircling the aforesaid intermediate spindle, is engaged with the aforesaid cam and is in operative connection with the moon-model spindle of angular cross-section to be moved by that spindle around the axis of the innermost spindle, a shadow-cap engaging one side of the moon-model, a rotatable driving-sleeve encircling the lower portion of the spindle by which as aforesaid the angular bore of the moon-model is engaged, two pulleys one fixed to the said driving-sleeve the other fixed to the horizontal bar aforesaid, and an endless band encircling these two pulleys, a rising and falling splined connection actuated by the rocking lever and also by the driving-sleeve and connecting said driving-sleeve and shadow-cap to turn the latter about the spindle of angular cross-section and to raise and lower the shadow-cap and moon-model band-tightening devices for the endless bands aforesaid and screw expanding-devices for the circumferences of driving wheels engaged by said bands.

9. In a tellurion, the combination of a base, a vertical shaft fixed in and extending upwardly from the base, a plurality of stationary wheels secured on the aforesaid vertical shaft and co-axial therewith, a horizontal bar pivoted to the aforesaid vertical shaft and movable about it in the horizontal plane, three concentric tubular spindles, innermost intermediate and outermost, together constituting a triple spindle and borne on one arm of the horizontal bar perpendicularly thereto and each rotatable independently of its companion about their common axis, three pulleys one secured to each of said three spindles, three endless bands constituting each an operative connection between a pulley on one of the said concentric spindles and a corresponding stationary wheel in the aforesaid plurality, an earth-model borne on the top of the innermost spindle, a cam fixed aslant upon the intermediate spindle, a moon-model bored axially, a spindle which at its upper end engages the moon-model and prevents relative rotation between it and the said spindle and at its lower end is operatively connected to the outermost of the three concentric tubular spindles aforesaid to turn therewith but not relatively thereto, an operative connection between the aforesaid cam and the moon-model to raise and lower that model by moving it along the spindle of angular cross-section, a rocking lever which is pivoted to a sleeve loosely encir-

- cling the aforesaid intermediate spindle, is engaged with the aforesaid cam and is in operative connection with the moon-model to raise and lower that model by moving it 5 along the spindle of angular cross-section and to be moved by the same spindle around the axis of the intermediate spindle, an earth-model, an inclined spindle about which that model is rotatable and which is 10 fixed to the innermost tubular spindle aforesaid and lies aslant in relation thereto, a driving wheel constituted by a series of radial arms having swan-necked ends and situated below the aforesaid base, a driving pinion secured to the earth-model, an auxiliary duplex pulley 70 carried on a support borne by the innermost tubular spindle, an endless band encircling the driving pinion and one member of the auxiliary duplex pulley, an endless band both sides of which pass through the bore of 75 the innermost tubular spindle and one end of which embraces the other member of the auxiliary duplex pulley while the other end encircles the said driving wheel, band-tightening devices for the endless bands aforesaid 80 and screw expanding-devices for the circumferences of driving wheels engaged by said bands. 15
10. In a tellurion, the combination of a base, a vertical shaft fixed in and extending upwardly from the base, a plurality of stationary wheels secured on the aforesaid vertical shaft and co-axial therewith, a horizontal bar pivoted to the aforesaid vertical shaft and movable about it in the horizontal plane, three concentric tubular spindles, innermost intermediate and outermost, together constituting a triple spindle and borne on one arm of the horizontal bar perpendicularly thereto and each rotatable independently of its companion about their common axis, three pulleys one secured to each of said three spindles, three endless bands constituting each an operative connection between a pulley on one of the said concentric spindles and a corresponding stationary 90 wheel in the aforesaid plurality, an earth-model borne on the top of the innermost spindle, a cam fixed aslant upon the intermediate spindle, a moon-model bored axially, a spindle which at its upper end engages the 95 moon-model and prevents relative rotation between it and the said spindle and at its lower end is operatively connected to the outermost of the three concentric spindles aforesaid to turn therewith but not 100 relatively thereto, an operative connection between the aforesaid cam and the moon-model to raise and lower that model by moving it along the spindle of angular cross-section, a rocking lever which is pivoted to a sleeve loosely encircling the aforesaid intermediate spindle, is engaged with the aforesaid cam and is in operative connection with the moon-model to raise and lower that model by moving it along the 105 spindle of angular cross-section and to be moved by the same spindle around the axis of the intermediate spindle, a sun-model, a rotatable sun-driving sleeve and pinion engaged with one another and encircling the 110 115 120 125 130

aforesaid vertical shaft, a stationary sun-driving wheel secured on the said vertical shaft, a vertical spindle fixed to and rising from the aforesaid horizontal bar, a pair of 5 connected auxiliary pulleys on that vertical spindle, flexible driving means operatively connecting the sun-driving pinion with the stationary sun-driving wheel by way of the said connected auxiliary pulleys, band-tightening devices for the endless bands aforesaid and screw expanding-devices for the circumferences of driving wheels engaged by said bands.

12. In a tellurion, the combination of a 15 base, a vertical shaft fixed in and extending upwardly from the base, a plurality of stationary wheels secured on the aforesaid vertical shaft and co-axial therewith, a horizontal bar pivoted to the aforesaid vertical 20 shaft and movable about it in the horizontal plane, three concentric tubular spindles, innermost intermediate and outermost, together constituting a triple spindle and borne on one arm of the horizontal bar perpendicular thereto and each rotatable independently of its companion about their 25 common axis, three pulleys one secured to each of said three spindles, three endless bands constituting each an operative connection between a pulley on one of the said concentric spindles and a corresponding stationary wheel in the aforesaid plurality, an earth-model borne on the top of the innermost spindle, a cam fixed aslant upon the 30 intermediate spindle, a moon-model bored axially, a spindle which at its upper end engages the moon-model and prevents relative rotation between it and the said spindle and at its lower end is operatively connected to the outermost of the three concentric 35 tubular spindles aforesaid to turn therewith but not relatively thereto, an operative connection between the aforesaid cam and the moon-model to raise and lower that 40 model by moving it along the spindle of angular cross-section, a rocking lever which is pivoted to a sleeve loosely encircling the aforesaid intermediate spindle, is engaged with the aforesaid cam and is in operative connection with the moon-model 45 spindle of angular cross-section to be moved by that spindle around the axis of the innermost spindle, a shadow-cap engaging one side of the moon-model, a rotatable driving-sleeve encircling the lower portion of the 50 spindle by which as aforesaid the angular bore of the moon-model is engaged, two pulleys one fixed to the said driving-sleeve the other fixed to the horizontal bar aforesaid, 55 and an endless band encircling these two pulleys, a rising and falling splined connection actuated by the rocking lever and also by the driving-sleeve and connecting said driving-sleeve and shadow-cap to turn the

latter about the spindle of angular cross-section and to raise and lower the shadow-cap and moon-model, an earth-model, an inclined spindle about which that model is rotatable and which is fixed to the innermost tubular spindle aforesaid and lies aslant in 70 relation thereto, a driving wheel below the aforesaid base, a driving pinion secured to the earth-model, an auxiliary duplex pulley carried on a support borne by the innermost tubular spindle, an endless band encircling the driving pinion and one member of the auxiliary duplex pulley, an endless band both sides of which pass through the bore of the innermost tubular spindle and one end of which embraces the other member of the auxiliary duplex pulley while the other end encircles the said driving wheel, a sun-model, a rotatable sun-driving sleeve and pinion engaged with one another and encircling the aforesaid vertical shaft, a 80 stationary sun-driving wheel secured on the said vertical shaft, a vertical spindle fixed to and rising from the aforesaid horizontal bar, a pair of connected auxiliary pulleys on that vertical spindle, flexible driving means operatively connecting the sun-driving pinion with the stationary sun-driving wheel by way of the said connected auxiliary pulleys, band-tightening devices for the 85 endless bands aforesaid and screw expanding-devices for the circumferences of driving wheels engaged by said bands.

13. In a tellurion, the combination of a base, a vertical shaft fixed in and extending upwardly from the base, a plurality of 100 stationary wheels secured on the aforesaid vertical shaft and co-axial therewith, a horizontal bar pivoted to the aforesaid vertical shaft and movable about it in the horizontal plane, three concentric spindles, innermost intermediate and outermost, together constituting a triple spindle and borne on one arm of the horizontal bar perpendicular thereto and each rotatable independently of its companion about their common axis, three pulleys one secured to each of said three spindles, three endless bands constituting each an operative connection between a pulley on one of the said concentric spindles and a corresponding stationary 105 wheel in the aforesaid plurality, an earth-model, borne on the top of the innermost spindle, a cam fixed aslant upon the intermediate spindle, a moon-model bored axially, a spindle which at its upper end engages the moon-model and prevents relative rotation between it and the said spindle and at its lower end is operatively connected to the outermost of the three concentric spindles aforesaid to turn therewith but not 110 relatively thereto, an operative connection between the aforesaid cam and the moon-model to raise and lower that model by 115

moving it along the spindle of angular cross-section, a rocking-lever which is pivoted to a sleeve loosely encircling the aforesaid intermediate spindle, is engaged with 5 the aforesaid cam and is in operative connection with the moon-model to raise and lower that model by moving it along the spindle of angular cross-section and to be moved by the same spindle around the axis 10 of the intermediate spindle and screw expanding-devices for the circumferences of driving-wheels engaged by said bands.

14. In a tellurion, the combination of a base, a vertical shaft fixed in and extending 15 upwardly from the base, a plurality of stationary wheels secured on the aforesaid vertical shaft and co-axial therewith, a horizontal bar pivoted to the aforesaid vertical shaft and movable about it in the horizontal 20 plane, three concentric spindles, innermost intermediate and outermost, together constituting a triple spindle and borne on one arm of the horizontal bar perpendicularly thereto and each rotatable independently of its companion about their 25 common axis, three pulleys one secured to each of said three spindles, three endless bands constituting each an operative connection between a pulley on one of the said concentric 30 spindles, and a corresponding stationary wheel in the aforesaid plurality, an earth-model borne on the top of the innermost spindle, a cam fixed aslant upon the intermediate spindle, a moon-model bored axially, a spindle which at its upper end engages the moon-model and prevents relative 35 rotation between it and the said spindle and at its lower end is operatively connected to the outermost of the three concentric spindles, aforesaid to turn therewith but not relatively thereto, an operative connection 40 between the aforesaid cam and the moon model to raise and lower that model by moving it along the spindle of angular cross- 45 section, a rocking lever which is pivoted to a sleeve loosely encircling the aforesaid intermediate spindle, is engaged with the aforesaid cam, and is in operative connection with the moon-model spindle of angular 50 cross-section to be moved by that spindle around the axis of the innermost spindle, a shadow-cap engaging one side of the moon-model, a rotatable driving-sleeve encircling the lower portion of the spindle by which 55 as aforesaid the angular bore of the moon-model is engaged, two pulleys one fixed to the said driving-sleeve the other fixed to the horizontal bar aforesaid, and an endless band encircling these two pulleys, a rising 60 and falling splined connection actuated by the rocking lever and also by the driving-sleeve and connecting said driving-sleeve and shadow-cap to turn the latter about the spindle of angular cross section and to

raise and lower the shadow-cap and moon- 65 model and screw-expanding-devices for the circumferences of driving-wheels engaged by said bands.

15. In a tellurion, the combination of a base, a vertical shaft fixed in and extending 70 upwardly from the base, a plurality of stationary wheels secured on the aforesaid vertical shaft and co-axial therewith, a horizontal bar pivoted to the aforesaid vertical shaft and movable about it in the horizontal 75 plane, three concentric tubular spindles, innermost intermediate and outermost, together constituting a triple spindle and borne on one arm of the horizontal bar perpendicularly thereto and each rotatable independently of its companion about their common axis, three pulleys one secured to each of said three spindles, three endless bands constituting each an operative connection 80 between a pulley on one of the said concentric spindles and a corresponding stationary wheel in the aforesaid plurality, an earth-model borne on the top of the innermost spindle, a cam fixed aslant upon the intermediate spindle, a moon-model bored 85 axially, a spindle which at its upper end engages the moon-model and prevents relative rotation between it and the said spindle and at its lower end is operatively connected to the outermost of the three concentric tubular spindles aforesaid to turn therewith but not relatively thereto, an operative connection 90 between the aforesaid cam and the moon-model to raise and lower that model by moving it along the spindle of angular cross-section, a rocking lever which is pivoted to a sleeve loosely encircling the aforesaid intermediate spindle, is engaged with the aforesaid cam and is in operative connection with the moon-model to raise and lower that 95 model by moving it along the spindle of angular cross-section and to be moved by the same spindle around the axis of the intermediate spindle, an earth-model, an inclined spindle about which that model is rotatable and which is fixed to the innermost tubular spindle aforesaid and lies aslant in relation thereto, a driving wheel below the aforesaid base, a driving pinion secured to the earth-model, an auxiliary duplex pulley 100 carried on a support borne by the innermost tubular spindle, an endless band encircling the driving pinion and one member of the auxiliary duplex pulley, an endless band 105 both sides of which pass through the bore of the innermost tubular spindle and one end of which embraces the other member of the auxiliary duplex pulley while the other end encircles the said driving wheel and screw-expanding-devices for the circumferences of driving-wheels engaged by said bands.

16. In a tellurion, the combination of a

base, a vertical shaft fixed in and extending upwardly from the base, a plurality of stationary wheels secured on the aforesaid vertical shaft and co-axial therewith, a horizontal bar pivoted to the aforesaid vertical shaft and movable about it in the horizontal plane, three concentric tubular spindles, innermost intermediate and outermost, together constituting a triple spindle and borne on one arm of the horizontal bar perpendicularly thereto and each rotatable independently of its companion about their common axis, three pulleys one secured to each of said three spindles, three endless bands constituting each an operative connection between a pulley on one of the said concentric spindles and a corresponding stationary wheel in the aforesaid plurality, an earth-model borne on the top of the innermost spindle, a cam fixed aslant upon the intermediate spindle, a moon-model bored axially, a spindle which at its upper end engages the moon-model and prevents relative rotation between it and the said spindle and at its lower end is operatively connected to the outermost of the three concentric tubular spindles aforesaid to turn therewith but not relatively thereto, an operative connection between the aforesaid cam and the moon-model to raise and lower that model by moving it along the spindle of angular cross-section, a rocking lever which is pivoted to a sleeve loosely encircling the aforesaid intermediate spindle, is engaged with the aforesaid cam and is in operative connection with the moon-model to raise and lower that model by moving it along the spindle of angular cross-section and to be moved by the same spindle around the axis of the intermediate spindle, an earth-model, an inclined spindle about which that model is rotatable and which is fixed to the innermost tubular spindle aforesaid and lies aslant in relation thereto, a driving wheel constituted by a series of radial arms having swan-necked ends and situated below the aforesaid base, a driving pinion secured to the earth-model, an auxiliary duplex pulley carried on a support borne by the innermost tubular spindle, an endless band encircling the driving pinion and one member of the auxiliary duplex pulley, an endless band both sides of which pass through the bore of the innermost tubular spindle and one end of which embraces the other member of the auxiliary duplex pulley while the other end encircles the said driving wheel, and screw expanding-devices for the circumferences of driving-wheels engaged by said bands.

17. In a tellurion, the combination of a base, a vertical shaft fixed in and extending upwardly from the base, a plurality of stationary wheels secured on the aforesaid vertical shaft and co-axial therewith, a horizontal bar pivoted to the aforesaid vertical shaft and movable about it in the horizontal plane, three concentric tubular spindles, innermost intermediate and outermost, together constituting a triple spindle and borne on one arm of the horizontal bar perpendicularly thereto and each rotatable independently of its companion about their common axis, three pulleys one secured to each of said three spindles, three endless bands constituting each an operative connection between a pulley on one of the said concentric spindles and a corresponding stationary wheel in the aforesaid plurality, an earth-model borne on the top of the innermost spindle, a cam fixed aslant upon the intermediate spindle, a moon-model bored axially, a spindle which at its upper end engages the moon-model and prevents relative rotation between it and the said spindle and at its lower end is operatively connected to the outermost of the three concentric spindles aforesaid to turn therewith but not relatively thereto, an operative connection between the aforesaid cam and the moon-model to raise and lower that model by moving it along the spindle of angular cross-section, a rocking lever which is pivoted to a sleeve loosely encircling the aforesaid intermediate spindle, is engaged with the aforesaid cam and is in operative connection with the moon-model to raise and lower that model by moving it along the spindle of angular cross-section and to be moved by the same spindle around the axis of the intermediate spindle, a sun-model, a rotatable sun-driving sleeve and pinion engaged with one another and encircling the aforesaid vertical shaft, a stationary sun-driving wheel secured on the said vertical shaft, a vertical spindle fixed to and rising from the aforesaid horizontal bar, a pair of connected auxiliary pulleys on that vertical spindle and flexible driving means operatively connecting the sun-driving pinion with the stationary sun-driving wheel by way of the said connected auxiliary pulleys, and screw expanding-devices for the circumferences of driving-wheels engaged by said bands.

18. In a tellurion, the combination of a base, a vertical shaft fixed in and extending upwardly from the base, a plurality of stationary wheels secured on the aforesaid vertical shaft and co-axial therewith, a horizontal bar pivoted to the aforesaid vertical shaft and movable about it in the horizontal plane, three concentric tubular spindles, innermost intermediate and outermost, together constituting a triple spindle and borne on one arm of the horizontal bar perpendicularly thereto and each rotatable independently of its companion about their common axis, three pulleys one secured to each of said three spindles, three endless bands constituting each an operative connection between a pulley on one of the said concentric spindles and a corresponding stationary wheel in the aforesaid plurality, an earth-model borne on the top of the innermost spindle, a cam fixed aslant upon the intermediate spindle, a moon-model bored axially, a spindle which at its upper end engages the moon-model and prevents relative rotation between it and the said spindle and at its lower end is operatively connected to the outermost of the three concentric spindles aforesaid to turn therewith but not relatively thereto, an operative connection between the aforesaid cam and the moon-model to raise and lower that model by moving it along the spindle of angular cross-section, a rocking lever which is pivoted to a sleeve loosely encircling the aforesaid intermediate spindle, is engaged with the aforesaid cam and is in operative connection with the moon-model to raise and lower that model by moving it along the spindle of angular cross-section and to be moved by the same spindle around the axis of the intermediate spindle, a sun-model, a rotatable sun-driving sleeve and pinion engaged with one another and encircling the aforesaid vertical shaft, a stationary sun-driving wheel secured on the said vertical shaft, a vertical spindle fixed to and rising from the aforesaid horizontal bar, a pair of connected auxiliary pulleys on that vertical spindle and flexible driving means operatively connecting the sun-driving pinion with the stationary sun-driving wheel by way of the said connected auxiliary pulleys, and screw expanding-devices for the circumferences of driving-wheels engaged by said bands.

- bands constituting each an operative connection between a pulley on one of the said concentric spindles and a corresponding stationary wheel in the aforesaid plurality, an 5 earth-model borne on the top of the innermost spindle, a cam fixed aslant upon the intermediate spindle, a moon-model bored axially, a spindle which at its upper end engages the moon-model and prevents relative 10 rotation between it and the said spindle and at its lower end is operatively connected to the outermost of the three concentric tubular spindles aforesaid to turn therewith but not relatively thereto, an operative 15 connection between the aforesaid cam and the moon-model to raise and lower that model by moving it along the spindle of angular cross-section, a rocking lever which is pivoted to a sleeve loosely encircling the 20 aforesaid intermediate spindle, is engaged with the aforesaid cam and is in operative connection with the moon-model spindle of angular cross-section to be moved by that spindle around the axis of the innermost 25 spindle, a shadow-cap engaging one side of the moon-model, a rotatable driving-sleeve encircling the lower portion of the spindle by which as aforesaid the angular bore of the moon-model is engaged, two pulleys 30 one fixed to the said driving sleeve the other fixed to the horizontal bar aforesaid, and an endless band encircling these two pulleys, a rising and falling splined connection actuated by the rocking lever and also by the 35 driving sleeve and connecting said driving-sleeve and shadow-cap to turn the latter about the spindle of angular cross-section and to raise and lower the shadow-cap and moon-model, an earth-model, an inclined 40 spindle about which that model is rotatable and which is fixed to the innermost tubular spindle aforesaid and lies aslant in relation thereto, a driving wheel below the aforesaid base, a driving pinion secured to 45 the earth-model, an auxiliary duplex pulley carried on a support borne by the innermost tubular spindle, an endless band encircling the driving pinion and one member of the auxiliary duplex pulley, an endless band both sides of which pass through 50 the bore of the innermost tubular spindle and one end of which embraces the other member of the auxiliary duplex pulley while the other end encircles the said driving 55 wheel, a sun-model, a rotatable sun-driving sleeve and pinion engaged with one another and encircling the aforesaid vertical shaft, a stationary sun-driving wheel secured on the said vertical shaft, a vertical 60 spindle fixed to and rising from the aforesaid horizontal bar, a pair of connected auxiliary pulley on that vertical spindle, and flexible driving means operatively connecting the sun-driving pinion with the sta- tionary sun-driving wheel by way of the 65 said connected auxiliary pulleys, and screw-expanding-devices for the circumferences of driving-wheels engaged by said bands.
19. In a tellurion, the combination of a base, a vertical shaft fixed in and extending upwardly from the base, a plurality of stationary wheels secured on the aforesaid vertical shaft and co-axial therewith, a horizontal bar pivoted to the aforesaid vertical shaft and movable about it in the horizontal plane, 70 concentric spindles constituting a compound spindle and borne on one arm of the horizontal bar perpendicularly thereto and each rotatable independently of its companion about their common axis, pulleys one secured 75 to each of said spindles, endless bands constituting each an operative connection between a pulley on one of the said concentric spindles and a corresponding stationary wheel in the aforesaid plurality, an earth-model borne on the top of the innermost spindle, a moon-model bored axially, a spindle which at its upper end engages the moon-model and prevents relative rotation between 80 it and the said spindle and at its lower end 85 is operatively connected to one of the concentric spindles appropriated thereto to turn with the spindle but not relatively thereto, and means to raise and lower the moon on its spindle. 90
20. In a tellurion, the combination of a base, a vertical shaft fixed in and extending upwardly from the base, a plurality of stationary wheels secured on the aforesaid vertical shaft and co-axial therewith, a horizontal bar pivoted to the aforesaid vertical shaft and movable about it in the horizontal plane, 95 concentric spindles constituting a compound spindle and borne on one arm of the horizontal bar perpendicularly thereto and each rotatable independently of its companion about their common axis, pulleys one secured 100 to each of said spindles, endless bands constituting each an operative connection between a pulley on one of the said concentric spindles and a corresponding stationary wheel in the aforesaid plurality, an earth-model borne on the top of the innermost spindle, a moon-model bored axially, a spindle which at its upper end engages the moon-model and prevents relative rotation between 105 it and the said spindle and at its lower end 110 is operatively connected to one of the concentric spindles appropriated thereto to turn with the spindle but not relatively thereto, and means to raise and lower the moon on its spindle. 115
21. In a tellurion, the combination of a base, a vertical shaft fixed in and extending upwardly from the base, a plurality of sta-

tionary wheels secured on the aforesaid vertical shaft and co-axial therewith, a horizontal bar pivoted to the aforesaid vertical shaft and movable about it in the horizontal plane, 5 concentric spindles constituting a compound spindle and borne on one arm of the horizontal bar perpendicularly thereto and each rotatable independently of its companion about their common axis, pulleys one secured 10 to each of said spindles, endless bands constituting each an operative connection between a pulley on one of the said concentric spindles and a corresponding stationary wheel in the aforesaid plurality, an earth- 15 model borne on the top of the innermost

spindle, a moon-model bored axially, a spindle which at its upper end engages the moon-model and prevents relative rotation between it and the said spindle and at its lower end is operatively connected to one of the concentric spindles appropriated thereto to turn with the spindle but not relatively thereto, means to raise and lower the moon on its spindle and screw expanding-devices for the circumferences of wheels engaged by said bands. 20 25

In testimony whereof I have signed my name to this specification.

WILLIAM WILSON.
